CLAIM

The ornamental design for a compartmented cart, as shown and described.

DESCRIPTION

FIG. 1 is a top left front perspective view of a compartmented cart showing my new design;

FIG. 2 is a front elevational view thereof;

FIG. 3 is a top plan view thereof;
FIG. 4 is a right side elevational view thereof; the left side elevational view being a mirror image;
FIG. 5 is a rear elevational view thereof;
FIG. 6 is a bottom plan view thereof.

The broken lines showing casters are for illustrative purposes only and form no part of the claimed design.
